(57) **CLAIM**

The ornamental design for a fluidic rotary mixer square icon
for a display screen, as shown and described.

DESCRIPTION

FIG. 1 is a front view of a fluidic rotary square mixer icon
for a display screen;

FIG. 2 is a front view of a second embodiment thereof;
FIG. 3 is a front view of a third embodiment thereof; and,
FIG. 4 is a front view of a fourth embodiment thereof.

The broken line drawing of a display screen in all views is
for illustrative purposes only and forms no part of the
claimed design.
